DESIGN FOR AN EDIBLE CONTAINER

Morris Kanfer, Woodridge, and Harry Bresnick, New York, N. Y.

Application January 3, 1935, Serial No. 54,712

Term of patent 7 years

To all whom it may concern:

Be it known that we, Morris Kanfer and Harry Bresnick, citizens of the United States and residents, respectively, of Woodridge, Sullivan County, State of New York, and of the city of New York, State of New York, have invented a new, original, and ornamental Design for Edible Containers, of which the following is a specification, reference being had to the accompanying drawing, forming part thereof.

Fig. 1 is a perspective view of the edible container, looking at the front thereof, showing our design.

Fig. 2 is a side view of the container,
Fig. 3 is a top view of the container, and
Fig. 4 is a bottom view of the container.

We claim:

The ornamental design for an edible container, as shown.
